UNITED STATES PATENT OFFICE

162,512

TABLE ORNAMENT

Anthony E. Bogdan, New Bedford, Pa.

Application December 10, 1949, Serial No. 6,553

Term of patent 3½ years

(Cl. D29—23)

To all whom it may concern:

Be it known that I, Anthony E. Bogdan, a citizen of the United States, residing at New Bedford, in the county of Lawrence and State of Pennsylvania, have invented a new, original, and ornamental Design for a Table Ornament, of which the following is a specification, reference being had to the accompanying drawing, forming a part thereof.

Figure 1 is a top plan view of a table ornament, showing my new design.

Figure 2 is a front view thereof.

The bottom is substantially plain.

I claim:

The ornamental design for a table ornament, as shown and described.

ANTHONY E. BOGDAN.
